SPRING STRUCTURE

William A. Clark, Detroit, Mich., assignor to L. A. Young Spring and Wire Corporation, Detroit, Mich.

Application September 10, 1934, Serial No. 743,329

4 Claims. (Cl. 155—180)

The main object of this invention is to provide an improved spring structure in which the springs in an open bottom cushion are effectively supported against sagging even when the cushion is arranged on an open or skeleton base.

A further object is to provide in a spring structure an improved spring connecting and supporting piece which is very rigid even when formed of comparatively light material.

10 Objects relating to details and economies of my invention will appear from the description to follow. The invention is defined and pointed out in the claims.

A structure which is a preferred embodiment 15 of my invention is illustrated in the accompanying drawing, in which:

Fig. 1 is a fragmentary top view of a cushion embodying the features of my invention.

Fig. 2 is an enlarged fragmentary view partially in vertical section.

Fig. 3 is a perspective view of a row of springs with their supporting and connecting pieces.

Fig. 4 is an enlarged detail section on line 4—4 of Fig. 3.

25 Fig. 5 is a detail section corresponding to that of Fig. 4 showing the relation of the spring to the cross piece before the cross piece is clamped thereon.

Figs. 6, 7 and 8 are cross sectional views of 30 modified forms of cross pieces.

In the embodiment of my invention illustrated, the border frame 1 is of the tacking strip type, the strip shown being that of the Falls Patent No. 1,899,188, dated February 28, 1933, the skirt 2 of the upholstery 3 being drawn over the edge of the rim or border frame and secured by tacks. The body springs 4 are of the helically coiled hour-glass type. The bottom coils of the border springs are secured to the rim by 35 clamping the rim flange 5 thereon. The springs are arranged in rows and the rows of springs are connected and supported by cross pieces 6 formed of metal strips.

40 In the embodiment shown in Figs. 1 to 5 inclusive, the upper portion of the strip is folded upon itself at 7 and terminates in a spring clamping flange 8. The lower portion of the strip is reversely folded upon itself at 9 and terminates in a spring clamping flange 10 parallel with the flange 8 and coacting therewith to form a channel receiving the bottom coils of a row of springs, the flange being clamped within the coils at 11, thereby effectively securing the supporting strips to the coils. These cross pieces or cross strips terminate adjacent the sides

of the border frame and are preferably only connected thereto through the end springs of the border springs of the rows as is shown in Fig. 1, which permits some freedom of movement of the cross pieces independent of the border frame 5 so that when the cushion is arranged upon an open base such as is very common in automobiles, the ends of the cross strips will overlie and rest upon the front and rear pieces of the base. By thus forming the cross pieces, they are very 10 rigid as the web portion of the channel is at least of double ply, a portion of it being triple ply in the embodiment shown in Figs. 4 and 5.

In the embodiment shown in Fig. 6, the upper portion of the strip is folded as in Figs. 4 15 and 5, but the lower portion is folded to provide a double ply bottom flange 12, the extreme edge portion of the strip being folded against the web portion of the strip. It will be noted that in this instance the web is double ply. 20

In the embodiment shown in Fig. 7, the upper edge of the strip is turned to provide a flange 13 while the fold 14 is approximately the full width of the strip, the fold 15 being of such width as to properly space the bottom flange 19 relative 25 to the flange 18.

In the embodiment shown in Fig. 8, the top flange 18 is folded the same as that of Fig. 7 and while the bottom flange 20 is positioned the same as the flange 19 of Fig. 7, it is of double 30

35 It will be noted that in all of these embodiments, the strip is folded so that at least a double thickness or double ply of material is provided in the vertical web portion of the cross piece. This results in a strip formed of comparatively light and easily bendable material, both in the initial forming and clamping upon the springs which is strong and resists springing in all directions and is capable of sustaining quite heavy loads even 40 when formed of relatively light material.

I have illustrated and described my improvements in very practical embodiments thereof. I have not attempted to illustrate or describe various modifications and adaptations of my improvements which I contemplate as it is believed this disclosure will enable those skilled in the art to embody or adapt my improvements as may be desired. 45

Having thus described my invention, what I claim as new and desire to secure by Letters Patent, is:

1. In a spring structure, the combination of a border frame and a plurality of rows of springs, the border springs being secured to said frame, 55

and cross pieces connecting the rows of springs each comprising a strip of metal having its upper edge folded upon itself and terminating in an upper spring clamping flange disposed centrally 5 of the cross piece and its bottom edge reversely folded upon itself and terminating in a lower spring clamping flange disposed approximately in the plane of the lower edge of the cross piece, said clamping flanges receiving the bottom coils 10 of a row of springs between them and being clamped thereon.

2. In a spring structure, the combination of a border frame and a plurality of rows of springs, the border springs being secured to said frame, 15 and cross pieces connecting the rows of springs each comprising a strip of metal folded longitudinally to provide an upper spring clamping flange, its bottom edge reversely folded upon itself and terminating in a lower spring clamping 20 flange, said clamping flanges receiving the bottom coils of a row of springs between them and being clamped thereon.

3. In a spring structure, the combination of a border frame, and a plurality of springs ar-

ranged in rows, the outer springs being secured to said frame, the rows of springs being connected by cross bars formed of strips of metal folded longitudinally to provide a double ply upright portion with its edges disposed to provide a channel portion receiving the bottom coils of a row of springs, the edges of the channel flanges being clamped within the coils, said channel portion including a multi-ply wall in vertical alinement with said double ply upright portion. 10

4. In a spring structure, the combination of a plurality of springs, and a connecting cross piece therefor comprising a strip of metal folded inwardly at its upper edge upon itself and terminating in a spring clamping flange disposed centrally 15 of the cross piece, the other edge being reversely folded upon itself and terminating in a spring clamping flange disposed in the plane of the lower edge of the strip and in opposed relation to the other clamping flange, said clamping 20 flanges receiving coils of the springs and being clamped thereon.

WILLIAM A. CLARK.
